GRINDER

Arthur L. Evans, Detroit, Mich.

Application September 17, 1941, Serial No. 411,097

3 Claims. (Cl. 51—166)

This invention relates to a grinder.

Heretofore it has been customary in grinders to mount the grinding or abrasive wheel directly on the shaft of an electric motor. The shaft of an electric motor invariably is loose and has considerable play in it. Due to this looseness or play in the mounting of the motor shaft, the grinding wheel necessarily has play or looseness in it. This play in the grinding wheel adversely affects the accuracy or precision obtainable in the grinding operation. To partially counteract the looseness in the grinding wheel it has been customary to use a wheel made from a fine grained abrasive. With a loose wheel a greater grinding precision is obtainable with a fine grained than with a coarse grained abrasive wheel. The disadvantage of a fine grained wheel over a coarse grained wheel is that the pores of the wheel become loaded with the metal or other material being ground faster than the coarser pores of the coarse grained wheel. This necessitates the more frequent dressing or truing of a fine grained wheel than a coarse grained wheel.

It is an object of this invention to produce a grinder which will grind with fine precision and which operates with greater efficiency than grinders heretofore used. This object is achieved by a particular mounting for the grinding wheel so that it is free from play or looseness both axially and transversely of the axis of rotation of the wheel.

The mounting of the grinding wheel so that it is free from play in all directions makes possible the use of a coarse grained wheel by means of which just as accurate grinding can be obtained as with a finer grained wheel and yet the need for frequent dressing down of the wheel is obviated.

In the fabricating of a grinding wheel it is practically impossible to uniformly distribute the weight of the wheel, that is, some areas will be denser and have a higher specific gravity than other areas. Due to this variation in density, any looseness or play in the mounting of the wheel will result in the wheel wobbling or vibrating while rotating. Even though a grinding wheel can wobble but very slightly due to play in its mounting shaft, the coarser the grain of the wheel the greater the gouging and the rougher the grind resulting from the play in the wheel mounting. If the wheel is held absolutely against play in all directions, then as precise a grind is obtainable with a coarse grained wheel as with a fine grained wheel. It is this object which is achieved by this invention.

In the drawings:

Fig. 1 is a side elevation showing the portable grinder.

Fig. 2 is a vertical axial section through the grinding wheel and mounting therefor.

Fig. 3 is a side elevation of the grinder viewed from the left hand side of Fig. 1.

Fig. 4 is a section along the line 4—4 of Fig. 3.

Fig. 5 is a section along the line 5—5 of Fig. 2.

Referring more particularly to the drawings, the grinder comprises a frame 1 which is mounted upon the wheels 2 so as to be portable from place to place in the shop where the grinder is used. A work support 3 is adjustably mounted on the frame 1 adjacent the abrasive wheel 4. This grinder is arranged to grind along the flat face 5 of the grinding wheel rather than along its circumferential face.

The grinding wheel comprises an abrasive wheel or ring 6 fixed on a rigid backing plate 7 of steel or other material. The plate 7 is backed up by another plate 8 of steel or other suitable material. The shaft upon which the wheel 4 is supported is designated 9.

Shaft 9 is provided adjacent one end with an integral flange 10. Wheel 4 and plate 8 are mounted over the stub end 11 of the shaft and rigidly secured thereto by bolts 12 which screw into the flange 10. The upper portion of the frame 1 is in the form of a housing 13 which serves as a support for the shaft 9. The shaft 9 is supported within the housing 13 by the thrust bearing races 14, 15 and 16. A cylindrical spacing sleeve 17 is mounted within the housing 13 and secured in place by the set screw 18 which interengages the sleeve 17 in the conical depression 19. Set screw 18 effectively locks sleeve 17 against any axial movement in the housing 13. The right-hand end of the shaft 9 is threaded as at 20 to receive the lock nut 21 and lock washer 22. A flexible coupling 23 connects shaft 9 with the shaft 24 of the motor 25. Motor 25 is secured to the frame 1 by bolts 26.

Shaft 9 is assembled in the housing as follows:

After sleeve 17 has been locked in the housing 13 by set screw 18, the bearing race 27 is mounted against flange 10 and over shoulder 28 on shaft 9. Thrust bearing races 14 and 15 are now placed over shaft 9 against circumferential shoulder 28. The shaft 9, with the bearings 27, 14 and 15, is now slipped into the left-hand end of housing 13 and passed through sleeve 17. Thrust bearing race 16, spacing ring 29 and bearing race 30 are now slipped over the right-hand end of shaft 9 and nut 21 is turned on to

the threaded end 20 of the shaft and turned down tight and then locked in place by lock washer 22. Turning of nut 21 causes the thrust bearings 14 and 15 to be held tightly between shoulder 28 on the shaft 9 and the sleeve 17. Ring 29 and thrust bearing race 16 are held tightly between the other end of the sleeve 17 and nut 21. Thus the ends of sleeve 17 act as shoulders within housing 13 which cooperate with shoulder 28, nut 21 and the thrust bearing races to hold shaft 9 against axial movement or play. Since bearing races 14, 15 and 16 have a precision fit with the shaft 9, the shaft is positively held in the housing 13 against any looseness or play transversely of the axis of the shaft. The nut 21 and shoulder 28 cooperate with the sleeve 17 and the thrust bearing races 14, 15, 16, and ring 29 to positively hold the shaft 9 against any axial movement.

A U-shaped guard 31 is provided for wheel 4. Guard 31 is mounted upon rods 33 which have an adjustable sliding fit in lugs 34 of housing 13. Rods 33 are held in their adjusted position by set screws 35. Guard 31, of course, is adjusted each time the flat face of the wheel 4 is dressed down. Housing 13 is provided with a reservoir 36 for oil or other lubricating fluid. Ring 37 fits loosely over shaft 9 and is suspended in the oil in reservoir 36. As the shaft 9 rotates, ring 37 also rotates and carries the oil from the reservoir 36 on to the shaft 9 and its supporting bearing races. Ring 37 is held in position on the shaft 9 by the oppositely tapered surfaces 40 and 41.

I claim:

1. In a grinding machine, a shaft adapted for supporting a grinding wheel, a shoulder on said shaft, a housing in which the shaft is mounted, a removable sleeve in said housing, means for positively securing said sleeve in place within and to the housing, thrust antifriction bearing races positioned on opposite sides of the sleeve in the housing for supporting the shaft in the housing free from play transversely of the shaft, and means carried by the shaft for placing the shaft in tension whereby one of the bearing races

is clamped between the shoulder on the shaft and one end of the sleeve in the housing and the other race is clamped between the said means and the other end of the sleeve in the housing to hold the shaft against axial play.

2. In a grinding machine, a shaft adapted for supporting a grinding wheel, a circumferential flange on said shaft, a housing in which the shaft is mounted, a removable sleeve in said housing positioned over said shaft and having substantially the same external diameter as the internal diameter of the housing, means for interengaging said sleeve and housing to lock said sleeve in place within and to the housing, thrust antifriction bearing races positioned on opposite sides of the sleeve in the housing for supporting the shaft in the housing free from play transversely of the shaft, and means carried by the shaft for placing the shaft in tension whereby one of the bearing races is clamped between the circumferential flange on the shaft and one end of the sleeve in the housing and the other race is clamped between the said means and the other end of the sleeve in the housing to hold the shaft against axial play.

3. In a grinding machine, a shaft adapted for supporting a grinding wheel, a circumferential flange on said shaft, a housing in which the shaft is mounted, a removable sleeve in said housing positioned over said shaft and having substantially the same external diameter as the internal diameter of the housing, means between said sleeve and housing for interlocking said sleeve in place within the housing and against longitudinal movement, thrust antifriction bearing races positioned on opposite sides of the sleeve in the housing for supporting the shaft in the housing free from play transversely of the shaft, a nut screwed on the shaft for placing the shaft in tension whereby one of the bearing races is clamped between the circumferential flange on the shaft and one end of the sleeve in the housing and the other race is clamped between the said nut and the other end of the sleeve in the housing to hold the shaft against axial play.

ARTHUR L. EVANS.
